UNITED STATES PATENT OFFICE.

ALFRED H. WOUTERS, OF NORWOOD, OHIO, ASSIGNOR TO ALLIS-CHALMERS COMPANY, A CORPORATION OF NEW JERSEY, AND THE BULLOCK ELECTRIC MANUFACTURING COMPANY, A CORPORATION OF OHIO.

TURBO-GENERATOR CONSTRUCTION.

No. 892,487.

Specification of Letters Patent.

Patented July 7, 1908.

Application filed November 3, 1906. Serial No. 341,812.

To all whom it may concern:

Be it known that I, ALFRED H. WOUTERS, belonging to the Kingdom of the Netherlands, residing at Norwood, in the county of 5 Hamilton and State of Ohio, have invented certain new and useful Improvements in Turbo-Generator Construction, of which the following is a full, clear, and exact specification.

10 My invention relates to dynamo-electric machines and particularly to high speed machines of the direct current type such as direct current turbo-generators.

In a high speed machine it is necessary to 15 provide means for holding in position the portions of the coils which project beyond the ends of the core, so that the coils can not be displaced by centrifugal action. It has been proposed to surround the coils by 20 heavy rings or bands made from some material such as phosphor bronze. When rings are employed for this purpose, it is necessary to provide some means for supporting, centering and retaining the rings in position.

25 In direct current machines, considerable difficulty has been experienced in providing adequate supporting and protecting means for the coils at the commutator end of the armature for the reason that the commutator 30 necks or leads connecting the coils to the commutator bars render difficult proper supporting of coil retaining rings. Accordingly band wires have usually been relied upon for retaining the projecting portions of the coils 35 in position. This latter expedient is not satisfactory for all types of machines particularly large high speed machines, for the reason that at high peripheral speeds, the band wires are in danger of breaking or becoming 40 loose and wrecking the machine.

The object of my invention is to provide improved means for supporting, centering, and retaining in position a ring for the projecting portions of the coils at the commutator end of the machine.

45 My invention consists in certain novel details of construction and combinations and arrangements of parts described in the specification and set forth in the appended claims.

50 For a better understanding of my invention, reference is had to the accompanying drawings in which

Figure 1 is a partial longitudinal sectional elevation of a machine equipped with my in-

vention; Fig. 2 is a transverse section of the 55 same substantially along the line 2—2 of Fig. 1 only a portion of the slots of the end member and conductors being shown; Fig. 3 is an enlarged plan view of a portion of the end-ring showing the ends of the spring- 60 locking device; Fig. 4 is a partial transverse section along the line 4—4 of Fig. 1, looking in the direction of the arrow; and Fig. 5 is a partial sectional view showing a slight modification.

65

Referring now to the figures of the drawings, 10 represents a shaft on which the core 11 and commutator 12 are mounted. The core consists of laminee held between end members one of which is shown at 13. The 70 armature is provided with a winding having portions 14 which project beyond the core and rest upon the shoulder or bracket 15 extending outwardly from the end-member 13. The end-member is also provided with a slot- 75 flange 16 through which the coils of the winding pass. At the outer end of the shoulder or bracket 15 are a plurality of outwardly extending teeth or projections 17. The coils extend through the slotted flange 16 80 as they emerge from the core and the ends of the coils pass through the slots or openings between the teeth 17 and extend a short distance beyond the latter (see Figs. 1 and 4). The coils 14 are separated from the 85 bracket 15 by insulation 18.

The bars 19 of the commutator 12 are held in position on the shaft by a plurality of shrink-rings 20. The commutator bars are connected to the ends 14 of the coils which 90 project beyond the teeth 17 by radial commutator leads or necks 21 which extend along the outer surface of the teeth and a short distance therefrom. These leads or necks are preferably riveted to the bars and 95 soldered to the ends of the coils.

Surrounding the projecting portions of the coils is a heavy rigid ring 22 having in this case a cylindrical portion 23 provided with a recessed or grooved portion 24 at the inner 100 end thereof fitting over the flange 16 of the end-member 13, and with an inwardly extending portion 25 at right angles to the cylindrical portion 23 and extending inward over the commutator necks. The ring rests 105 on and fits tightly over the teeth of the slotted flange 16 and on the teeth 17 which are turned down in a lathe so as to have true

outer surfaces relative to the axis of the machine. Thus it is seen that the ring is well supported and centered.

I have provided novel means for locking and retaining the end-ring 22 in position as will now be described. The flange 16 of the end-member is provided with a continuous groove 26, and the recessed portion of the ring 22 is provided on its inner side with a groove 27, the grooves 26 and 27 being so located, that when the ring is in position with the shoulder on the ring engaging the flange, the two grooves exactly register or coincide. The groove in the ring is preferably semi-circular in cross section and preferably extends entirely around the ring. Communicating with this groove are two adjacent L-shaped open slots 28 and 29 having parallel end-portions extending outward to the inner edge of the ring (see Fig. 3). The groove 26 in the flange 16 is preferably deeper than the groove 27 as will be explained, the bottom of the groove being also preferably semi-circular in cross section. Located in the grooves in the ring and flange is a ring-shaped spring locking rod 30 having ends which extend outward a short distance in the open slots 28 and 29. The rod is in this case circular in cross section having a diameter the same or slightly less than the diameter of the semi-circular groove 27, and is made from material having considerable elasticity so that it tends to spread outward or to expand, filling the semi-circular groove 27. The groove 26 has a depth equal to or slightly greater than the thickness of the spring locking rod 30. Thus it is seen that when the end-ring is in position the locking rod assumes a position shown in Figs. 1, 2 and 3, the outer half being in the groove 27 and the lower half being in the groove 26 so as to prevent the end-ring from slipping outward. When it is desired to remove the ring, the two ends of the spring locking rod are drawn together to the position shown in dotted lines in Fig. 3, decreasing the diameter of the ring until it is located entirely within the slot 26 in the flange. Since the outwardly extending ends of the spring locking rod are now opposite the parallel ends of open slots 28 and 29 the end-ring can be removed longitudinally, and again replaced when desired without difficulty. It is seen that when the armature is rotated the ring is also locked through the action of centrifugal force which tends to hold the spring locking ring in the outer groove, or in the locking position.

While I have shown a locking rod circular in cross section it is evident that the rod may be of any other cross section, such as rectangular. In the latter case the grooves in the ring and end-member would of course have a corresponding shape so that the rod would have a good close fit therein.

In Fig. 5 I have shown a slight modification of the end-ring. In this case the end-

ring 22^a does not extend over the commutator necks but only a short distance beyond the radial teeth 17 on the bracket. The use of an end-ring as here shown has the advantage that the commutator necks can be connected to or disconnected from the coils without necessitating a removal of the end-ring. The ring 22^a is supported, centered, and locked into position as is the ring 22 first described.

While I have in this case shown a specific form of centering means for the outer portion of the end-ring, consisting of teeth integral with the shoulder or bracket, I wish it to be understood that any other form of centering means may be employed if desired with my improved end-ring locking device. In some instances the ring may need no further centering means than the ends of the coils themselves.

It is apparent that my invention is susceptible of changes or modifications without departing from its spirit and scope, and I aim in my claims to cover all such modifications.

What I claim as new and desire to secure by Letters Patent is:—

1. In an armature of a dynamo-electric machine, a core and end-member, conductors carried by said core and having projecting portions resting on said end-member, commutator connections a ring surrounding the projecting portions of said conductors and extending over and protecting said commutator connections, and means for retaining said ring in position comprising a readily removable spring locking device located between the end-members and the ring and protected by said ring.

2. In an armature of a dynamo-electric machine, a core and end-member, conductors carried by said core and having projecting portions resting on said end-member, a ring surrounding the projecting portions of said conductors, and means for retaining said ring in position comprising a readily removable spring rod between and engaging said ring and end-member.

3. In an armature of a dynamo-electric machine, a core, and end-member, conductors carried by said core and having projecting portions resting on said end-member, a ring surrounding said projecting portions of the coils, and means for retaining said ring in position comprising a readily removable ring-shaped or circular spring rod engaging said ring and end-member and lying within said ring so as to be protected thereby.

4. In an armature of a dynamo-electric machine, a core and end-member, conductors carried by said core and having projecting portions resting on said end-member, a ring surrounding said coils and resting on said end-member, said ring and end-member having respectively internal and external

registering grooves, and a readily removable contractible rod normally located in both said grooves.

5. In an armature of a dynamo-electric machine, a core, coils carried thereby and projecting beyond the end thereof, a bracket on which the projecting portions of the coils rest, a ring surrounding the projecting portions of the coils, and means for supporting and centering said ring and for spacing and positioning the projecting portions of the coils comprising radial teeth or fingers at the outer end of the bracket.

6. In an armature of a dynamo-electric machine, a core, and an end-member comprising a toothed flange and a bracket or shoulder having teeth at its outer end, coils carried by said core and having projecting portions resting on said bracket, and extending between said teeth, and a ring surround-

ing said projecting portions of the coils and resting on the teeth of said flange and said bracket.

7. In an armature of a dynamo-electric machine, a core, and an end-member comprising a toothed flange and a bracket or shoulder having teeth at its outer end, coils carried by said core and having projecting portions resting on said bracket, and extending between said teeth, a ring surrounding said projecting portions of the coils and resting on the teeth of said flange and said shoulder, and means for locking said ring to said end-member.

In testimony whereof I affix my signature, 35
in the presence of two witnesses.

ALFRED H. WOUTERS.
